(57) **CLAIM**

The ornamental design for a medicine container, as shown and described.

DESCRIPTION

FIG. 1 is a perspective view of a medicine container

illustrating my new design with the view taken from above and in front of the medicine container;

FIG. 2 is a perspective view of the medicine container of FIG. 1 illustrating my new design with the view taken from below and behind the medicine container;

FIG. 3 is a front view of the medicine container of FIG. 1;

FIG. 4 is a back view of the medicine container of FIG. 1;

FIG. 5 is a top view of the medicine container of FIG. 1;

FIG. 6 is a bottom view of the medicine container of FIG. 1;

FIG. 7 is a right side view of the medicine container of FIG. 1;

FIG. 8 is a left side view of the medicine container of FIG. 1;

FIG. 9 is perspective view of the medicine container of FIG. 1 with a lid of a base container open and a medicine tray insert removed from the base container;

FIG. 10 is a perspective view of the medicine container of FIG. 1 with the lid open and a thirty two compartment medicine tray insert in the base container;

FIG. 11 is a perspective view of the medicine container of FIG. 1 with the lid open and a fourteen compartment medicine tray insert in the base container;

FIG. 12 is a perspective view of a medicine container illustrating my new design wherein the base container is translucent, the lid is raised and a fourteen compartment medicine tray insert is in the base container; and,

FIG. 13 is a perspective view of a medicine container illustrating my new design wherein the base container is translucent, the lid is raised and a thirty two compartment medicine tray insert is in the base container.
